(57) **CLAIM**

The ornamental design for a rail for receiving an accessory as shown and described.

DESCRIPTION

FIG. 1 is a perspective view of the rail for receiving an accessory;

FIG. 2 is a back elevational view of the rail for receiving an accessory;

FIG. 3 is a front elevational view of the rail for receiving an accessory;

FIG. 4 is a top plan view of the rail for receiving an accessory;

FIG. 5 is a bottom plan view of the rail for receiving an accessory;

FIG. 6 is a right side elevational view of the rail for receiving an accessory;

FIG. 7 is a left side elevational view of the rail for receiving an accessory;

FIG. 8 is a left side elevational view of the rail for receiving an accessory with a first accessory attached; and,

FIG. 9 is a left side elevational view of the rail for receiving an accessory with a second accessory attached.

The dashed broken lines define the bounds of the claimed design and form no part thereof. Additional broken lines in FIGS. 8-9 are directed to environment that form no part of the claimed design.

1 Claim, 8 Drawing Sheets
